T. J. KINDELEBERGER, OF EATON, OHIO.

Letters Patent No. 80,635, dated August 4, 1868.

IMPROVEMENT IN WATER-WHEELS.

The Schedule referred to in these Letters Patent and making part of the same.

TO ALL WHOM IT MAY CONCERN:

Be it known that I, T. J. KINDELEBERGER, of Eaton, in the county of Preble, and State of Ohio, have invented certain new and useful Improvements in Water-Wheels; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists, first, in a novel construction of the plates and buckets of the wheel itself; and, second, in a novel arrangement of devices for closing and opening the gates.

Figure 1 is a side elevation of the wheel, with a portion of the lower plate broken away to more clearly exhibit the form of the bucket.

Figure 2 is a vertical section, showing the form of the plates or rims.

Figure 3 is a top plan view of the wheel-case, exhibiting the devices for operating the buckets, and Figures 4 and 5 views illustrating the angles of the buckets.

My present invention has for its object the construction of a wheel which shall more fully utilize the power of the water, and also enable the gates to be opened and closed rapidly and easily.

My improved wheel I construct with two series of buckets, placed one above the other, and held in place between annular rims and plates, similar to some of those formerly patented to me, but differing both in the form of the plates and of the buckets. The upper plate, A, I make whole, in the form of a disk, recessed on the top from the inner edge of the buckets to the hub at the centre, through which the shaft D passes, and to which it is keyed fast. From the outer edge, this plate extends inward horizontally for one-fifth the width of the space occupied by the buckets E, and thence inclines downward, at an angle of thirty-five degrees, to the inner edge of the buckets, as represented in fig. 2, from which point it extends inward horizontally to the hub at the centre. I then construct an annular rim, B, similar in form, but having its horizontal portion two-ninths of its width, and the remaining portion inclining at an angle of forty-one degrees.

Between these two, the plate A and the rim B, I secure the upper tier of buckets, E, as shown in fig. 1. These buckets are curved, so that their upper ends will assume the form indicated by the line *n* in fig. 5; the outer concave portion receiving the impact of the water as it first enters the wheel between the gates J, which are located vertically at various points in the case surrounding the wheel, and operating, when open, as guides to direct the water upon the buckets, as indicated by the arrows in fig. 1, in which a couple of the buckets J are shown in position.

These buckets, E and F, consist of plates of iron, cast solid with the plate and rims, or of steel plates, made separately, and having the plate and rims cast on them, and they are placed so that their outer edges incline forward fifteen degrees from the perpendicular, as shown in fig. 4, those of one tier standing midway between those of the other tier, as shown in fig. 1. The buckets E have their inner lower corner curved backward, as indicated at *o*, fig. 2, thereby imparting to them a slightly-spiral form, the inner lower portion inclining more and more towards a horizontal position, so that the water shall continue to press upon it as long as there is any force left in it.

The lower rim, C, has its outer portion made horizontal for one-eighth of its width, the remaining seven-eighths inclining downward at an angle of seventy degrees, as shown in figs. 1 and 2. Between this rim C and the rim B, I locate the lower tier of buckets, F, the outer edges of which incline fifteen degrees, the same as those above. The inner edges of the buckets F are curved, as shown at *f*, fig. 2, from the point *o*, at the inner edge of the rim B, to the point *a*, at the lower inner edge of the rim C, the point *a* being bent or curved backward for a much greater distance than those of the buckets E, as shown in fig. 1, where the rim C is broken away, the lower portion of these buckets F standing at an inclination of about twenty-three degrees from the horizontal, as represented in fig. 4. Both tiers of buckets are so located, that when a line, *t*, is drawn, as rep-

resented in fig. 5, so as to intersect the two edges of the bucket, and a line, r , is drawn from the inner edge of one bucket to intersect the outer edge of the next one, the two lines, t and r , shall form an angle of thirty-one degrees, as there shown, the line t intersecting the extremities of the bucket, thus forming an angle of fifty-nine degrees with a line drawn horizontally across the centre of the wheel, these lines being all taken at the top edge of the buckets. By this peculiar construction and arrangement of the buckets and rims, I produce a wheel that is exceedingly efficient in utilizing the power of the water.

The case, with its gates, I construct on the same plan as in my patent of March 19, 1867, but the devices for operating the gates I construct on a different plan. In that, I used a worm-wheel for moving the plate G, to which the rods l connect the gates. In practice, I find the worm-wheel objectionable, for the reason that it is too slow in its operation. In my present improved plan, I use a pinion, I, secured to a vertical shaft, which is provided at its upper end with a hand-wheel for turning it. This pinion is arranged to gear into and move a segmental rack, which is pivoted upon the top plate L of the case, at its opposite end, as shown at b , fig. 3, and this rack, H, I connect to the plate or collar G by a rod or bar, P, so as to form a knuckle-joint, whereby great power is brought to bear upon and turn the collar G, and thereby to close and open the gates J with ease. By this arrangement of devices, the gates can be closed or opened with but little effort, and with much greater rapidity than by the worm-wheel formerly used.

Having thus described my invention, what I claim, is—

1. The water-wheel, consisting of the plate A and rims B and C, with the two tiers of buckets, E and F, all constructed and arranged substantially as herein described.
2. The rim C and buckets F, when constructed and combined as set forth.
3. The combination of the pinion I, segmental rack H, rod P, and collar G, when arranged in connection with the case and vertical gates of a water-wheel, as herein shown and described.
